UNITED STATES PATENT OFFICE

WILLIAM F. WRIGHT, OF YORK, AND JOHN S. JENKS, OF PITTSBURGH, PENNSYLVANIA,
ASSIGNORS TO WRIGHT MANUFACTURING COMPANY, OF YORK, PENNSYLVANIA, A
CORPORATION OF DELAWARE

DERRICK

Application filed February 11, 1930. Serial No. 427,470.

Our invention relates to derricks and the like and has for a specific object to provide a novel hoisting device adapted particularly for removing and replacing the bushings of large 5 transformers and circuit breakers, although obviously the invention is not limited to such application but may be used also for handling other objects as well.

Heretofore, considerable difficulty has been 10 experienced in handling large transformer and circuit-breaker bushings because the bushings are heavy, bulky and fragile and must be handled with care to avoid the danger of breaking or otherwise injuring them. The 15 handling of these bushings is usually attended with difficulty because of the proximity of high tension wires with obvious danger if the bushing, the rigging or the workmen strike these wires.

20 An object of our invention, therefore, is to provide a very simple form of derrick with which a bushing may be raised out of and lowered into the socket therefor in a transformer, or circuit breaker.

25 Another object is to provide means for turning the bushing about a transverse axis so that it will clear the transformer tank or circuit-breaker tank and also any overhead wires as it is being transferred to or from 30 the tank.

Another object of the invention is to provide a hoisting device which will require a minimum of space laterally to prevent contact with high tension wires at either side.

35 Another object of the invention is to provide a very simple anchorage for the legs of the derrick which may be applied to a transformer or circuit-breaker tank with a minimum of effort.

40 Another object is to provide means on the derrick by which attachment may be made to the flange of the bushings and also to render said attachment means adjustable for bushings of different size.

45 These and other objects of our invention

will appear in the following specification of a preferred embodiment and thereafter the novelty and scope of the invention will be pointed out in the claims.

In the accompanying drawings; 50 Figure 1 is a side elevation of our improved derrick, showing the device in the act of removing a circuit-breaker bushing from a circuit-breaker, and also showing in broken lines the position of the bushing after it has 55 been removed and placed on a suitable support;

Fig. 2 is a fragmentary view of a portion of the derrick looking in the direction of the arrows 2—2 of Fig. 1; 60

Fig. 3 is a front elevation of the derrick looking in the direction of the arrows 3—3 of Fig. 1;

Fig. 4 is a view in section taken substantially 65 on the line 4—4 of Fig. 3; and

Fig. 5 is a detail view, in section, of a clamping device, the section being taken on the line 5—5 of Fig. 4.

In the drawings, we have used the numeral 70 10 to indicate a circuit-breaker tank in which is fitted a bushing 11. The latter is provided with the usual insulator members 12 and attachment flange 13 which rests upon a socket flange 14 in the tank. The bushing is provided with the usual depending shank portion 75 15 which fits into the circuit-breaker or transformer as the case may be.

Our improved derrick is provided with 80 means for anchoring the legs thereof to the tank 10, said means consisting of an arcuate anchor band 16 preferably adapted to fit upon the bottom flange 17 of the tank. The anchor band terminates in a pair of up-standing ears 18 through which are passed hook bolts 19 adapted to engage hand holds 20 85 formed in the wall of the tank. Connecting each ear 18 to the anchor band is a pair of side flanges 21 which provide bearings for a hinge pin 22. Hinged upon the pins 22 are the legs 90 23 of the derrick. As shown in the drawings,

the legs of the derrick may consist of sections of pipe. The pipes 23 are connected at the top by a pair of tubular members 24 and 25, fixed by means of yoke clamps 24a and 25a respectively to the pipes 23. Running through the member 24 is a shaft 26; secured to this shaft and journaled in the yokes 24a are drums 28 about which are wound guy lines 29. These guy lines are secured at 10 their outer ends to a suitable anchorage, such, for instance, as a socket flange on the far side of the tank 10. Mounted on one end of the shaft 26 is a standard chain hoist mechanism 30 provided with a sprocket wheel 31 bearing the usual hoisting chain 32. Thus, by pulling on the chain 32 the guy lines are taken in or paid out, thereby controlling the angle of the derrick legs with respect to the anchorage. It will be observed that each hook bolt 15 19 is attached to the anchorage band at a point above the pivot pins 22, so that there will be no tendency for the anchorage band to lift away from the tank, but instead it will be pressed down against the flange 17 of the tank 20 by the thrust of the derrick legs 23.

Within the member 25 there is shaft 27. Secured to this shaft and journaled in the yokes 25a are drums 33. At one end of the shaft 27, and preferably on the opposite side 30 of the derrick from the mechanism 30, is a standard chain hoist 34 provided with the usual sprocket wheel 35 controlled by a chain 36. Thus, by pulling on the chain 36 the shaft 27 may be rotated and the drums 33, fixed thereon will take up or pay out a pair of cables 37 which lead to a pair of carriages 38, slideable along the derrick legs 23.

The carriages 38 are preferably provided with rollers 39 bearing on opposite sides of 40 each derrick leg. Journaled in the carriages 38 is a transverse shaft 40 which is adapted to be turned by a standard chain hoist mechanism. It will be understood that the chain hoist mechanism referred to in connection 45 with this shaft and the shafts 26 and 27 may be of any suitable type in which the rotation of the driven shaft may be controlled and maintained at any desired position, either by non-reversible gearing or suitable automatic 50 brake mechanism.

By way of illustration, we have shown a specific form of hoisting mechanism in connection with shaft 40, but it will be understood that our invention is not limited to this 55 particular type of hoisting mechanism. As illustrated, the shaft 40 has a worm wheel 41 fixed thereon and the latter is engaged by a worm 42 on a transverse shaft 43. The shaft 43 in turn is connected by a pair of miter 60 gears 44 to a shaft 45 and the latter carries a sprocket wheel 46 provided with an operating chain 47, so that by pulling on the chain 47 the shaft 40 may be turned through any angle desired.

Fixed to the shaft 40 is a spanner plate

48 to which the flange of the bushing 11 is attached. The spanner plate is formed with a recess 49 adapted to receive the flange 13 of the bushing and secured upon the plate 48 are a number of clamps 50 by which attachment 70 may be made to the flange. In order to provide for bushings of varying diameters, each clamping block is formed with a slot 51 through which bolts 54 are passed and screwed into the spanner plate 48. Each 75 clamp is thus adjustable lengthwise on the spanner plate. The outer end of the clamping block is apertured to receive a bolt 52 by which it is secured to the bushing. The flange 13 of the bushing is normally formed with slots 53 to receive the bolts by which it is clamped to the socket flange 14, as shown at 55 in Fig. 5, and the same slots 53 are used to receive the bolts 52 by which the flange of the bushing is clamped to the spanner plate 48.

The operation of the device is as follows: Assuming that it is desired to remove a bushing from a transformer or circuit-breaker tank, the anchorage band of the derrick is 50 first applied to the bottom of the tank and made fast thereto by taking up on the hook bolts 19. The guy lines 29 are then made fast to one of the socket flanges 14 on the far side of the tank, and the chain 32 is 55 operated to take up on the guy lines so as to draw the derrick up to a position slightly inclined from the vertical, as shown in Fig. 1. At the same time the chain 36 is operated to bring the spanner plate 48 into proper 60 position with respect to the flange of the bushing. The chain 47 is operated to turn the shaft 40, so that the spanner plate will lie normal to the axis of the bushing. The bolts 55 are then removed and the bushing is 65 bolted to the clamping blocks 50, the latter being clamped at suitable adjustment on the spanner plate. After this, the chain 36 is operated to draw the bushing upward until the shank clears the transformer shell. Then 70 the chain 47 is operated to turn the shank forward so that the bushing will lie substantially transverse to the plane of the derrick. Thereafter, the chain 32 is operated to lower 75 the derrick to the position shown in broken lines in Fig. 1 and at the same time the chain 47 is operated to turn the bushing to a horizontal position, or a position parallel 80 to that of a suitable support 56. This support may be the body of a truck on which the bushings are transported to and from the transformer.

In applying a new bushing to the tank the operations are reversed. The derrick is 85 raised by drawing on the chain 32 and the bushing is turned to such position as to enter the socket in the tank by operating the chain 47, after which the chain 36 is operated to lower the bushing into its socket. The 90 bolts are then undone to release the bushing 95

from the spanner plate and the bushing is then bolted to the socket flange 14 in the usual manner. The derrick is readily attached to and detached from the tank, so that it may be moved from one tank to another as needed.

The foregoing description is to be considered as illustrative and not limitative of our invention and it will be understood that various changes may be made in form, construction and arrangement of parts without departing from the spirit and scope of our invention.

We claim:

1. A derrick comprising a longitudinal supporting member, an attachment device supported thereby and including means for clamping a load to said device, means for moving said device lengthwise of the supporting member, and means for rotating said device.

2. A derrick comprising an upright, an attachment device supported thereby and including means for clamping a load to said device, means for raising and lowering said device along the upright, and means for turning said device about an axis transverse to that of the upright.

3. A derrick comprising a longitudinal supporting member, a plate-like member supported thereon, a clamping device adjustable on the plate member, means for moving said plate lengthwise of the supporting member, and means for turning the member about an axis transverse to that of the supporting member.

4. A derrick comprising a longitudinal supporting member, a plate-like member supported thereon, a clamping device adjustable on the plate member, self-locking means for moving said plate lengthwise of the supporting member, and self-locking means for turning the member about an axis transverse to that of the supporting member.

5. A derrick comprising an upright, a transverse shaft supported thereon, an attachment device secured to the shaft and including means for clamping a load to said device, means for moving the shaft lengthwise of the upright, and means for rotating the shaft.

6. A derrick comprising a pair of uprights, means for holding the same in mutually spaced relation, a saddle mounted to move lengthwise of each upright, means for raising and lowering the saddles, a shaft journaled in said saddles, means for rotating the shaft, and an attachment device carried by and rotatable with said shaft.

7. A derrick comprising a pair of uprights, means for holding the same in mutually spaced relation, a saddle mounted to move lengthwise of each upright, self-locking means for raising and lowering the saddles, a shaft journaled in said saddles, self-

locking means for rotating the shaft, and an attachment device carried by and rotatable with said shaft.

8. A derrick comprising an anchorage, an upright hinged thereto, means for varying the angle of the upright with respect to the anchorage, an attachment device carried by the upright, means for moving the attachment lengthwise of the upright, and means for turning the attachment device about an axis transverse to that of the upright.

9. A derrick comprising an anchorage, an upright hinged thereto, means for varying the angle of the upright with respect to the anchorage, an attachment device carried by the upright, self-locking means for moving the attachment device lengthwise of the upright, and self-locking means for turning the attachment device about an axis transverse to that of the upright.

10. A derrick comprising an anchorage, an upright hinged thereto, self-locking means for varying the angle of the upright with respect to the anchorage, an attachment device carried by the upright, self-locking means for moving the attachment device parallel to the longitudinal axis of the upright, and self-locking means for turning the attachment device about an axis transverse to that of the upright.

11. A derrick for inserting bushings into and removing bushings from a tank, said derrick comprising an anchorage band, means for attaching the band to the tank, a longitudinal supporting member hinged to the band, means for varying the angle of the supporting member with respect to the band, an attachment member carried by the supporting member, clamps for securing a bushing to the attachment member, and means for moving the attachment member lengthwise of the support.

12. A derrick for inserting bushings into and removing bushings from a tank, said derrick comprising an anchorage band, means for attaching the band to the tank, a longitudinal supporting member hinged to the band, means for varying the angle of the supporting member with respect to the band, an attachment member carried by the supporting member, clamps for securing a bushing to the attachment member, means for moving the attachment member lengthwise of the support, and means for turning the attachment member about an axis transverse to that of the supporting member.

13. A derrick for inserting bushings into and removing bushings from a cylindrical tank, said derrick comprising an arcuate anchorage band adapted to fit a cylindrical portion of the tank, means for attaching the band to the tank, a longitudinal supporting member hinged to the band, means for varying the angle of the supporting member with respect to the band, an attaching member car-

ried by the supporting member, clamps for securing a bushing to the attachment member, means for moving the attachment member lengthwise of the supporting member, and means for turning the attachment member about an axis transverse to that of the bushing.

14. A derrick for inserting bushings into and removing bushings from a tank, said derrick comprising an anchorage adapted to be secured to the tank, a longitudinal supporting member hinged to the anchorage, means for varying the angle of the supporting member with respect to the anchorage, a plate member carried by the supporting member and formed with an arcuate recess to receive a bushing, clamps adapted to clamp the bushing to the plate member, and means for moving the plate member lengthwise of the supporting member.

15. A derrick for inserting bushings into and removing bushings from a tank, said derrick comprising an anchorage adapted to be secured to the tank, a longitudinal supporting member hinged to the anchorage, means for varying the angle of the supporting member with respect to the anchorage, a plate member carried by the supporting member and formed with an arcuate recess to receive a bushing, clamps readily adjustable on the plate and adapted to clamp the bushing to the plate member, and means for moving the plate member lengthwise of the supporting member.

16. A derrick for inserting bushings into and removing bushings from a tank, said derrick comprising an anchorage adapted to be secured to the tank, a longitudinal supporting member hinged to the anchorage, means for varying the angle of the supporting member with respect to the anchorage, a plate member carried by the supporting member and formed with an arcuate recess to receive a bushing, clamps readily adjustable on the plate and adapted to clamp the bushing to the plate member, means for moving the plate member lengthwise of the supporting member, and means for turning the plate member about an axis transverse to that of the supporting member.

17. A derrick comprising an anchorage, an upright hinged thereto, a drum for a guy line mounted on the upright, a hoisting drum also mounted on the upright, an attachment device mounted to slide lengthwise of the upright, a line connected to the attachment device and wound about the hoisting drum, a self-locking gear for turning each of said drums, and a chain belt for operating each of the self-locking gears.

18. A derrick comprising an anchorage, an upright hinged thereto, a drum for a guy line mounted on the upright, a self-locking gear for turning each of said drums, a support slidably lengthwise of the upright, a line con-

nected to the support and wound about the hoisting drum, an attachment device carried by the support and mounted to turn about an axis transverse to the axis of the upright, a self-locking gear for turning said attachment device, and a chain belt for operating each of the self-locking gears.

In testimony whereof, we have signed this specification.
